Wallace R. Lane, Atty.

UNITED STATES PATENT OFFICE

ALEXANDER D. ELLIOTT, OF CHICAGO, ILLINOIS

FABRIC HOLDING DEVICE

Application filed December 1, 1930. Serial No. 499,189.

The present invention relates to fabric holding devices, and more in particular to clasp mechanisms for holding garments, and the like, in position upon the wearer.

5 Among the objects of the present invention is to provide a novel fabric holding device comprising members adapted to uniformly grip a piece of fabric or material therebetween.

10 The invention comprehends the idea of providing a clasp mechanism for uniformly gripping a piece of fabric so that the fibers of the fabric or material are evenly stretched or stressed, thus preventing damage to the fabric. The present novel clasp is especially adapted for gripping and holding said materials or fabrics, such as ladies' stockings, undergarments, or the like, whereby the same may be effectively held in position without

20 fear of damaging the same.

At the present time, clasps of the type herein disclosed are provided with a round or substantially round knob and a securing member adapted to fit over and engage therewith, the material being held between these members. That portion of the material fitting over and around the knob is unevenly stretched by the securing means, thus causing uneven stresses in the fiber. Individual 25 strands or fibers become unduly elongated and worn, and break, causing "runs" or other damage to the fiber.

30 It is, therefore, an object of the present invention to provide a clasp mechanism adapted to uniformly grip a piece of material so that the same is evenly held between the members of the mechanism.

In an illustrative embodiment selected to disclose the invention, the gripping members 35 of the clasp are flat and of substantial width so that each of the strands or fibers of the material engaged by these members, is subjected to a straight longitudinal pull only.

Another object of the present invention is 40 to provide a novel means for and method of covering the present novel clasp, whereby the metallic part of the clasp will not come into contact with the body of the wearer.

The invention comprehends the idea of providing a supporting fabric for securing the

clasp mechanism to the wearer and for covering the rear portion of the mechanism, whereby the parts of the clasp will not come into direct contact with the wearer. In the illustrative embodiment selected to illustrate 55 the invention, one end of the supporting fabric is attached to the clasp mechanism while an intermediate portion thereof is folded upon itself to provide a loop engaged by other parts of the mechanism. The clasp mechanism is accordingly efficiently held in position for use, as likewise covered for preventing the wearer from coming into direct contact therewith.

60 Other objects, features, capabilities and advantages are comprehended by the invention, as will later appear, and as are inherently possessed thereby.

Referring to the drawings:

Fig. 1 is a view in perspective of the present novel clasp mechanism, disclosing the same in a closed position and gripping a piece of fabric between the members thereof.

Fig. 2 is a view in perspective of the embodiment disclosed in Fig. 1 of the drawings, 75 and showing the gripping member in an open position.

Figure 3 is a longitudinal cross sectional view of the embodiment of the invention disclosed in Figs. 1 and 2 of the drawings. 80

Fig. 4 is a longitudinal cross sectional view of the end portion of one of the members of the clasp mechanism, disclosing the manner in which the end thereof is fabricated for holding the end of the supporting fabric, as 85 likewise provide means for gripping the fabric inserted between the same and the other member of the clasp mechanism.

Fig. 5 is a longitudinal cross sectional view similar to Fig. 4, and disclosing in detail the 90 finished rolled end of edge of one of the members of the clasp mechanism.

Referring now more in particular to the drawings, the embodiment selected to illustrate the invention is disclosed as comprising a member 1 adapted to be positioned beneath or on one side of a piece of fabric, and a jaw member 2 adapted to grip the piece of fabric and to hold the same in the clasp mechanism.

The member 1 comprises an elongated piece of metal stamped or otherwise cut from a sheet of metal, the body portion of this piece being bent along the line 1^a as clearly shown in Fig. 3 of the drawings. This bent portion of member 1 has certain portions of its outer edge rolled to provide the hinge elements 3 and 4, while the other end of the member 1 is bent or rolled in a manner to be later more fully disclosed.

The jaw member 2 comprises a movable member 5 and a fabric engaging element 6. This member 5 is stamped or otherwise cut from a piece of sheet metal and has a central edge portion bent or rolled to provide a hinge element 7 adapted to fit between the hinge elements 3 and 4 of the member 1. This member 5 is further provided with an elongated projecting tongue 8, on either side of which, the edge of the member is bent or rolled to provide the hinge elements 9 and 10 adapted to receive portions of the fabric engaging element 6. This garment engaging member or element 6 is formed from wire and is bent to provide the outer nose portion 11, the ends of this piece of wire engaging in the hinge elements 9 and 10 of the member 5. The member 5 and the member 1 are secured together by a pintle member 12 adapted to pass through the hinge elements 3 and 4 of the member 1, and the hinge element 7 of member 5. This pintle member 12 has its ends bent toward the rear of the member 1 and into a position substantially parallel to the hinge mechanism, for a purpose to be later more fully described.

In order to connect the clasp mechanism to the wearer, a piece of supporting fabric 13 is provided and may have its free end secured to a belt, undergarment, or other similar clothing, the other end thereof being secured or attached to the clasp mechanism. This supporting fabric is connected to the clasp mechanism in such a manner as to entirely cover the rear portion thereof and to prevent any part of the mechanism from coming into contact with the wearer.

In securing this fabric to the clasp mechanism, the outer end of the member 1 is partially bent, as shown in Fig. 4 of the drawings, and the end of the supporting fabric 13 folded thereover. This outer end of the member 1 is then pressed so that the end is in a plane substantially parallel to the plane of the member. The end of the fabric 13 is securely held between this folded edge and the main portion of the member 1. After the fabric 13 has been secured in this manner, the end portion of the member 1 is again partially folded into a position as clearly shown in Fig. 5 of the drawings, to provide an edge 14 adapted to receive the nose portion 11 of the fabric engaging element 6. The other end of the supporting fabric 13, previous to the connecting of the same to the

wearer, is then threaded through the opening between the bent end portions of the pintle 12 and the member 1, after which an intermediate portion of the fabric 13 is folded upon itself, as at 15, to provide a loop portion 16 adapted to engage with the bent end portions of the pintle 12. The supporting fabric 13 may then be sewed as at 17 and 18 to securely connect or attach the other end of the clasp mechanism to this fabric. It will be readily seen from this construction that the entire rear portion of the clasp mechanism is covered so as to protect the wearer from coming into direct contact with the various parts of this mechanism.

As clearly shown in the drawings, a piece of fabric, such as 19 may be placed over the member 1 and the nose piece 11 moved in the direction of the space between the edge 14 and the main part of the member 1. The nose portion 11 of the fabric engaging member 6 may then be moved into its most forward position by pressing on the tongue 8 of the member 5, whereby the jaw of the clasp mechanism is locked in an engaging position, as clearly shown in Fig. 3 of the drawings.

The jaw is locked in its engaging position during the final movement of the tongue member 8 into the position shown in Fig. 3 of the drawings. During this final movement of the tongue member 8, the hinge connection between the members 5 and 6 moves inwardly toward the member 1 and out of alignment with a plane passing through the nose 11 and the pintle 12, thus the fabric engaging element 6 is sufficiently off center so as to prevent outward movement of the same and the disengagement of the fabric 19 from the clasp mechanism. The fabric 13 covering the rolled edge of the member 1 further provides a contacting surface for the fabric 19 which prevents any tendency of slippage of the fabric 19 between the jaw 6 and member 1.

It will be seen that those portions of the fabric engaged by the members 1 and 6 lay flat therebetween and are uniformly gripped thereby. Inasmuch as both the member 1 and the nose piece 11 of the fabric engaging element 6 are of substantial width, each of the threads or strands of that portion of the fabric engaged by the members will be evenly stressed, thereby eliminating undue wear or other damage to the fabric or material.

While I have herein described and upon the drawings shown an illustrative embodiment of the invention, it is to be understood that the invention is not limited thereto, but may comprehend other constructions, arrangements of parts, details and features without departing from the spirit of the invention.

Having thus disclosed the invention, I claim:

1. A fabric holding device comprising a member adapted to be positioned beneath a

piece of fabric, a jaw hinged to said member, said jaw comprising a movable part and a fabric engaging part adapted to engage an end of the fabric and grip the same between
5 said engaging part and member, said movable part being provided with a projecting tongue overlying said fabric engaging part and adapted to clamp or release the fabric upon movement thereof, a pintle member for
10 said hinge, said pintle member having its ends bent rearwardly and substantially parallel to said hinge, and a supporting fabric for holding said device in position and for covering the rear portion thereof, said fabric
15 having an end secured to said member and having an intermediate portion folded upon itself and adapted to engage with the ends of said pintle member.

2. A fabric holding device comprising a
20 member adapted to be positioned beneath a piece of fabric and provided near its top with a bent portion, hinge elements provided on said bent portion, a jaw hinged to said hinge elements, said jaw being provided with
25 a fabric engaging part and a movable part adapted to cause said engaging part to engage or disengage the fabric, said movable part having a projecting tongue adapted to overlap said engaging part and be readily
30 grasped by the wearer for attachment or detachment of the device, a pintle member for said hinge elements, said pintle member having its ends bent rearwardly and substantially parallel to said hinge elements, and a
35 supporting fabric for holding said device in position and for covering the rear portion thereof, said fabric having an end secured to said member and having an intermediate portion folded upon itself and adapted to engage
40 with the ends of said pintle member.

3. A fabric holding device comprising a member adapted to be positioned beneath a piece of fabric, hinge elements provided on said member, a jaw hinged to said hinge elements, hinge elements provided on said jaw, said jaw being provided with a fabric engaging part hingedly connected to the hinge elements on said jaw, and a movable part adapted to cause said engaging part to engage or disengage the fabric, said movable part having a tapered projection overlying said engaging part and adapted to be readily grasped by the wearer for attachment or detachment of the device, a pintle member for
50 the hinge elements on said member, and a supporting fabric for holding said device in position and for covering the rear portion thereof, said fabric having an end secured to said member and having an intermediate portion
55 folded upon itself and adapted to engage with the ends of said pintle member.

In witness whereof I hereunto subscribe my name to this specification.
